HUGO JUNKERS, OF AIX-LA-CHAPELLE, GERMANY.

PISTON OF ENGINES, COMPRESSORS, MOTORS, AND OTHER MACHINES HAVING RECIPROCATING PISTONS.

1,102,590.

Specification of Letters Patent.

Patented July 7, 1914.

Application filed November 30, 1912. Serial No. 734,254.

To all whom it may concern:

Be it known that I, HUGO JUNKERS, a subject of the King of Prussia, residing at No. 68 Bismarckstrasse, Aix-la-Chapelle, in the Kingdom of Prussia, Empire of Germany, have invented certain new and useful Improvements in and Relating to the Pistons of Engines, Compressors, Motors, and other Machines Having Reciprocating Pistons; and I do hereby declare the following to be a full, clear, and exact description of the invention, such as will enable others skilled in the art to which it appertains to make and use the same.

15 This invention relates to machines having reciprocating pistons in which the pistons are subject to a high degree of heat on one end thereof in addition to great mechanical stress, such, for instance, as gas and oil engines, compressors, and the like. In such machines it is desirable that the heat be distributed or conducted away as quickly as possible in order to guard against distortion and breakage of the piston as much as possible. Various means have heretofore been employed to this end, such, for instance, as the provision of heat radiating ribs, the provision of a water circulation to and from the piston, and conducting heat from the piston to the cylinder wall which latter is cooled by air or water. The cooling of the piston by conducting cooling water to and from the same involves considerable difficulty both in the construction 30 of the machine and in its operation, as such water must be conveyed to and from a piston which is reciprocating with considerable velocity and, furthermore, the reciprocating movement given to the cooling water in the piston interferes with the continuous flow of the water in the same direction. The cooling of the piston merely by the provision of radiating ribs which increase the surface exposed to the air is insufficient for 45 machines of large sizes in which relatively high temperatures exist, as the transfer of heat from metal to the surrounding air due merely to contact of the air with the metal, is relatively slow. The same is true of the transfer of heat from a piston to the walls of the inclosing cylinder, particularly with respect to the central portion of the head of the piston.

50 This invention is directed to the provision of improved means for cooling a piston in-

volving the distribution of heat which is produced at one point on or over one wall of the piston to the whole of the piston, so that stresses concentrated over a substantially small portion of the piston are 60 avoided. With the constructions heretofore employed, heat developed at the center of the operative face of the piston has been conducted to the cylindrical wall merely by the metal of the cylinder itself so that such 65 heat has been transmitted a substantial distance through metal of comparatively small cross-section in order to reach the points of lower temperature. In accordance with this invention, however, the piston is made hollow and a liquid is provided within the cavity in the piston completely inclosed within the piston; this liquid transfers heat directly from the operative face of the piston to the cylindrical wall and other parts 70 which are of relatively low temperature and which are in contact with the cooler portions of the cylinder itself. To increase the effect of this liquid inclosed within the hollow piston, I provide means for causing a circulation of the cooling water whereby a more rapid and thorough distribution of the heat is effected. For this purpose, ribs may be provided upon the interior surface of the hollow piston, or balls, or other loose bodies 75 may be provided within the piston which are caused to move to and fro therein by the reciprocating movement of the piston. Such bodies moving within the piston, serve to effect circulation of the water and even 80 transfer heat directly from one end of the piston to the other.

I have illustrated an embodiment of my invention in the accompanying drawing, in which—

Figure 1 is a longitudinal section through an internal combustion engine; Fig. 2 is a longitudinal section through the piston; Fig. 3 is a transverse section on the line A, A, of Fig. 2; Fig. 4 is a transverse section 100 on the line B, B, of Fig. 2.

Referring to these drawings, the engine is shown as provided with a cylinder 1, having a cooling jacket 2, and the end of the cylinder is closed by a head 3, in which are 105 arranged the devices for controlling the supply of gas or other fuel, air and cooling water flowing to and from the water jacket 2. Within the cylinder 1, is a reciprocating piston 4, the movement of which is trans-

mitted by the rods 5 and crank 6, to the shaft of the engine, and the fly-wheel 7. In this engine the combustible mixture is ignited in the chamber between the head 3 and the 5 adjacent end of the piston 4 and the central portion of that end of the piston is continuously heated to a relatively high degree. The other end of the piston, however, is never in direct contact with the combustible 10 mixture so that its temperature would be substantially lower than that of the opposite end of the piston if the construction heretofore commonly employed were used. In the construction shown, however, the 15 piston 4 is made hollow and within the closed cavity in the piston is a substantial amount of water or other liquid preferably filling the cavity to the extent indicated at 8, in Fig. 2. When the piston so constructed is reciprocated within the cylinder of the engine, the water flows to and fro within the cavity in the piston. As shown in Fig. 1, the piston is in the dead point at the left end of its reciprocating movement and the 20 whole of the end of the piston which comes in contact with the combustible mixture is covered by the water. When the piston is at the other end of the stroke, the opposite end of the piston and the cylindrical walls 25 adjacent thereto will be covered with water; therefore, during each stroke of the piston, the heat which has been taken up by the end of the piston from the explosive gases 30 will be taken up by the water and distributed over the other walls of the piston as a result of which all parts of the piston will be maintained at a substantially uniform temperature. In order to facilitate the transfer of the heat from the end of the 35 piston which is in contact with the explosive gases, I provide the interior surface of that end of the piston with a plurality of projections 9, and one or more similar projections may be provided upon the cylindrical wall of the piston adjacent to that end. These projections enlarge the heat 40 radiating surface and furthermore they serve to increase the circulation of the water within the closed cavity in the piston. The 45 cylindrical wall of the piston may be provided with ribs 10 which extend either longitudinally or spirally relatively to the axis of the piston. These ribs aid in effecting the circulation of the water within the piston. After operation of the engine for a 50 substantial period of time, the water within the piston will be heated to a relatively high temperature, but even then this water 55 within the piston will serve to attain the main object of the invention which is an 60

even distribution of the heat over the whole of the piston. I have found that the great difference of temperature between different parts of the piston of an engine of this character, has always been a source of great 65 danger in engines constructed in the manner heretofore common. With the construction herein shown, smooth operation of the engine is readily obtained, particularly as to lubrication of the interior of the cylinder, and the piston may be readily effected due largely to the fact that the piston is maintained at a substantially uniform temperature throughout all parts thereof. Moreover, the construction adopted for the 70 piston may be governed largely by principles of strength instead of making parts of the piston of a cross-section greater than that required for strength in order to secure the necessary radiation of heat through the 75 walls thereof. Furthermore, by this construction, distortion of the piston caused by the unequal heating of the different parts thereof is avoided.

In the drawings, I have shown the piston as provided with but one cavity, but in some cases, I may provide two or more such cavities by arranging divisional walls within the piston; also, I have referred to the liquid within the piston as being water, 80 but it is to be understood that any other liquid may be employed, if desired.

What I claim is:

1. In an engine, a cylinder, a piston reciprocating in the cylinder and having a 95 cavity formed therein which is completely closed, and a liquid in the cavity, which liquid, by its movement in the cavity in the piston, transmits heat from the highly heated portions to the less heated portions of 100 the piston; substantially as described.

2. In an engine, a cylinder, a piston reciprocating in the cylinder and having a cavity formed therein which is completely closed, a liquid within the cavity, and means 105 for causing circulation of the liquid within the cavity as the cylinder is reciprocated; substantially as described.

3. In an engine, a cylinder, a hollow piston reciprocating therein, a liquid confined 110 within but not filling the hollow piston, and ribs formed on the interior walls of the hollow piston; substantially as described.

In testimony thereof I have signed my name to this specification in the presence of 115 two subscribing witnesses.

HUGO JUNKERS.
